UNITED STATES PATENT OFFICE.

ENRIQUE VINCKE, OF BARCELONA, SPAIN.

GUN WAD OF CORK MATERIAL.

No Drawing.

Application filed September 25, 1923. Serial No. 664,788.

To all whom it may concern:

Be it known that I, ENRIQUE VINCKE, a citizen of the German Empire, residing at Barcelona, Spain, have invented certain new and useful Improvements in Gun Wads of Cork Material, of which the following is a specification.

This invention relates to gun wads formed of cork material.

Heretofore it has been proposed to form gun wads of cork by subjecting a mass of cork granules admixed with an adhesive to pressure as in a mold to form a rod and to sever such rod to form the wads of the desired thickness. In such gun wads, the cork particles are substantially as in so-called composition cork for closures, gaskets and the like, and of the same form as natural cork, that is to say, having pores as inherently present in natural cork, and accordingly capable of absorbing moisture and other foreign material. It has been further proposed to treat such composition cork wads with a hygroscopic substance such as glycerin or gelatin, usually together with a coagulant such as formalin, for the purpose of preventing the cork from drying out and thereby shrinking and permitting access of moisture of the atmosphere to the powder. However, such composition gun wads have proven objectionable by reason of the moisture content effected by the hygroscopic substance.

Pursuant to my invention, the wads are formed of granules of natural cork, without any binding material, by subjecting to pressure and at such elevated temperature whereby the cork is fused into a substantially homogeneous mass, and preferably in a

mold.

By such procedure, I obtain wads which are absolutely water proof, inherently flexible and wholly devoid of pores. Wads produced according to my invention, possess a structure of substantial uniformity and thereby provide for the maximum ballistic efficiency of the explosive charge.

Gun wads embodying my invention, by reason of their intricate composition, resist any tendency to be chipped or broken off. 50

It will be understood that the process of fusing the cork material by application of heat and pressure, in order to obtain a water proof material, is not novel with me and I do not claim such process per se as a part 55 of my invention.

If desired, the product of the heat and pressure treatment may be in the form of a continuous web, as by feeding cork material to an endless band of steel passing through 60 an oven or series of ovens and associated with a series of rollers for effecting increasing pressure and consequent reduction in volume of the cork on the steel band in the travel through the oven or ovens until the 65 required pressure and temperature are attained for fusing the cork material into the homogeneous mass.

Whereas I have described my invention by reference to specific forms thereof, it will 70 be understood that many changes and modifications may be made without departing from the spirit of the invention.

I claim:

1. A gun wad formed from particles of 75 natural cork fused together by pressure and heat solely and without any adhesive, resulting in a substantially homogeneous and water proof mass and devoid of pores.

2. A gun wad formed from natural cork 80 subjected to pressure and heat to form an autogeneous mass substantially wholly devoid of pores.

3. A gun wad formed from particles of natural cork autogeneously bonded to one 85 another without any adhesive and substantially wholly devoid of pores.

In testimony whereof I have signed this specification this 19th day of September, 1923.

ENRIQUE VINCKE.

Certificate of Correction.

It is hereby certified that in Letters Patent No. 1,546,419, granted July 21, 1925, upon the application of Enrique Vineke, of Barcelona, Spain, for an improvement in "Gun Wads of Cork Material," an error appears in the printed specification requiring correction as follows: Page 1, line 49, for the word "intricate" read *integral*; and that the said Letters Patent should be read with this correction therein that the same may conform to the record of the case in the Patent Office.

Signed and sealed this 22d day of September, A. D. 1925.

[SEAL.]

KARL FENNING,
Acting Commissioner of Patents.
